TOOL

William A. Woerner, Elizabeth, N. J., assignor to
Worthington Pump and Machinery Corpora-
tion, New York, N. Y., a corporation of Virginia

Application January 27, 1934, Serial No. 708,601

2 Claims. (Cl. 77—58)

This invention relates to tools and more particularly to locking means for detachably securing various types of machine tools, such as counterborers, milling cutters, facing cutters, etc., to the shank or holder employed in connection with various types of machines, such as drill presses, millers, boring machines, and the like.

The present practice comprises various means of attaching tools of the types above referred to, to the shanks or holders, such as by means of bayonet slots, wedge keys, or the like, and unless special provision is made, the tool is unidirectional. The locking means also are subjected to considerable localized stresses resulting in an unnecessary high degree of wear and breakage. The tool can be adjusted axially only in relatively large increments, if at all. Hence, only rarely could more than one tool be employed at a time on a single shank or holder.

In the present invention the above mentioned disadvantages of prior art practices have been overcome through the use of an improved locking means which rigidly secures the tool to the holder at any desired position.

The primary object, therefore, of the present invention is to provide a tool having locking means which will firmly secure one or more tools to a holder or shank at any desired axial position, and in such manner that as the load on the tool increases the gripping action of the locking means will increase proportionately.

Another object is to provide locking means which will distribute the stresses from the tool over a relatively large portion of the shaft.

With these objects in view, the invention consists of various features of construction and combination of parts, which will be first described in connection with the accompanying drawing, showing a tool of the preferred form embodying the invention, and the features forming the invention will be specifically pointed out in the claims.

In its preferred form, the invention comprises a tool bored for mounting upon holder or shank and having an internal, eccentric channel adapted to receive a ring-like split sleeve. The tool body is adapted to wedge the sleeve against the holder following relative motion between the tool and holder.

In the drawing:

Fig. 1 is an elevational view of two tools on a holder in operating position.

Fig. 2 is a cross sectional view taken on the lines 2—2 of Fig. 1.

Fig. 3 is a longitudinal sectional view taken on the lines 3—3 of Fig. 2.

Fig. 4 is an isometric view of the locking collar. In the drawing, the invention has been shown applied to a double-edged spot facing tool, but it is to be understood that the invention will work equally well when used in conjunction with a trepanner, a counterbore, or any other similar tool. In the specification and claims the term "tool" will be used to designate the hollow-body secured to the shank. Referring again to the drawing, the invention comprises in the preferred embodiment, a holder or tool shank 10. A tool 11 is bored axially to freely receive the holder 10. The tool 11 is provided with a plurality of cutting edges 12 and a tool body 13. A locking sleeve or ring 14 is positioned in an annular channel 15 cut in the tool body 13. The locking sleeve or ring 14 is a curved wedge of substantially crescent shape, and is preferably made of a strip of hard, resilient material, such as spring steel, adapted to be sprung into the annular channel upon assembly. The locking sleeve 14 has a turned-in lug 16, adapted to engage in a longitudinal groove or slot 17, provided in the shaft 10. The locking ring 14 is thicker at its mid-section and tapers gradually toward its two ends. The ring 14 is shown in Figs. 2 and 4 as an open ring or annular wedge, but if desired it may be extended to form an eccentric annulus, split to permit assembly, the inside of which in either case is concentric to receive the cylindrical holder 10.

The annular channel 15 is eccentric with respect to the bore of the tool 11. When the thickest portion of the sleeve is matched with the deepest portion of the annular channel, the tool may be made to slide freely on the holder by aligning the lug 16 with the groove 17.

To secure the tool to the shaft for operating condition, the tool is adjusted axially to the desired position. Locking action is obtained by rotating the tool with respect to the shaft. During rotation of the tool the sleeve 14 is held against rotary motion with respect to the shaft by the engagement of the lug 16 in the groove 17. As the tool is rotated, the eccentric shape of the annular channel will cause the sleeve to act as a wedge and become firmly bound between the tool holder and the tool, and further relative movement between tool and holder will be prevented. In Fig. 2, the tool is shown in a locked position, the tool being ready to operate in a clockwise direction.

To unlock the device for removal of the tool from the holder, it is simply necessary to maintain

the tool holder in a stationary position and to revolve the tool in a clockwise direction until the shank or holder 10 is once again free in the locking sleeve 14. The tool may then be adjusted 5 axially or removed if desired. The tool also may be locked for use in the opposite direction by rotating the tool body in a clockwise direction from the neutral position until the wedging action again takes place. Substantially one-half of the 10 sleeve becomes wedged between the tool and the holder under either operating position.

The device is self-locking in either direction and it is not necessary for the operator to touch the tool after he has once located it in the correct 15 axial position on the holder. The tool may be unlocked manually without the use of a wrench. As seen in Fig. 2, the locking sleeve contacts the shaft for approximately one-half of its circumference. This provision allows for even distribution 20 of the stresses acting between the tool and the holder. There is no tendency for the locking device to fail by shearing action as the ring 14 is subjected almost completely to simple compression. The gripping action of the wedge increases 25 with the torque on the tool so that slippage is eliminated. It may thus be seen that by means of the present invention the tool may be locked and unlocked respectively by a short twist of the tool with respect to the shaft, after which the tool may 30 be removed completely from the holder. No bayonet slots are required, and the tool may be positioned at any desired point on the holder. This factor admits of the use of multiple tools on 35 a single holder, spaced according to the requirements of the work and adapting the tool to perform multiple operations simultaneously. In Fig. 1 of the drawing, the tool is shown ready to per-

form a double spot-facing operation on a yoke (indicated in broken lines), after the respective tools have been properly spaced axially. The readiness with which the tool may be removed facilitates its use for facing and backfacing operations. If, when the tool is being placed on the shaft, the sleeve is not correctly matched with the eccentric channel, alignment may be obtained by engaging the lug 16 in the groove 17 and rotating the tool until it slides freely on to the shaft. Locking action is obtained by further rotating the tool in either direction while holding the shaft.

It will be understood that the invention is not to be limited to the specific construction or arrangement of parts shown, but that these may be modified widely within the invention defined by the claims.

What is claimed is:

1. The combination, with a holder, of a tool normally free to rotate and to slide axially on said holder, said tool having an eccentric bored portion, and locking means comprising a split annulus having a concentric inner portion adjacent to said holder and an eccentric outer portion conforming with the eccentric bored portion of said tool.
2. In a tool assembly, a cylindrical grooved holder, a tool provided at its bored portion, with an annular eccentric channel, locking means comprising a discontinuous annulus of substantially crescent shape, means on said locking means for engaging said grooved holder, said locking means having an inner contour concentric with and adjacent to said holder, and an outer contour eccentric with respect to said holder and adjacent to said eccentric channel.
